UNITED STATES PATENT OFFICE.

ROBERT FRANCIS ARMSTRONG, OF LA CYGNE, KANSAS.

GOPHER GUN.

Application filed March 7, 1921, Serial No. 450,272. Renewed December 29, 1922.

To all whom it may concern:

Be it known that I, ROBERT FRANCIS ARMSTRONG, a citizen of the United States, and a resident of La Cygne, in the county of 5 Linn and State of Kansas, have invented certain new and useful Improvements in Gopher Guns, of which the following is a specification.

The present invention relates to improvements in guns especially adapted for use in 10 killing gophers and other undesirable animals.

The object of the invention is to provide an improved gun of this character which is 15 of simple and durable construction, reliable in operation and easy and inexpensive to manufacture, which is operated by the gopher when the gopher is in the line of fire whereby destruction is made certain 20 and which is adapted to be positioned so as to be most effective and efficient in carrying out its purposes.

Other objects and advantages of the invention reside in certain novel features of 25 construction, combination and arrangement of parts which will be hereinafter more fully described and particularly pointed out in the appended claims, reference being had to the accompanying drawings forming part 30 of this specification, and in which:

Figure 1 is a side elevational view of the invention;

Figure 2 is a view in longitudinal vertical section;

Figure 3 is a plan view;

Figure 4 is a view in transverse section on line 4—4 of Figure 1;

Figure 5 is a detail perspective view of the hammer and associated parts;

Figure 6 is a similar view of one of the coacting trip levers; and

Figure 7 is a similar view of the other coacting trip lever.

Referring to the drawings wherein for the sake of illustration is shown the preferred embodiment of the invention, the numeral 10 designates generally a frame constructed of two parts indicated at 11, and 12, which are secured together by suitable fastening means as for instance a bolt and nut 13 (see Figure 4). The part 11 of the frame carries a single leg 14 which is pointed at its lower end, as at 15, whereby it may be forced firmly into the ground to anchor the

frame. A pair of diverging legs 16 are arranged at the rear of the frame and carried by the part 12 thereof. 55

A breech 17 is carried by the part 12 of the frame, preferably by being formed integral therewith. The breech is provided with a cavity 18 and with a bore 19 which communicates with the cavity. The forward end of the cavity is internally threaded and engages the externally threaded end 21 of a barrel 22. A firing pin, designated generally at 23, is mounted in the bore 19 of the breech and has a striker 24 at its inner end and an annular enlargement or impact surface 25 at its outer end. A hammer 27 coacts with the firing pin, and has an impact surface 28 provided thereon for contact with the impact surface 25 of the firing pin. A finger piece 27^a extends laterally from the hammer and permits of the ready manipulation of the same. The hammer 27 is pivotally mounted upon the frame, preferably by means of a compound lever 29 upon the arm 30 of which the hammer 27 is carried. The compound lever is provided with a second arm 31 which is received in a slot 12^a provided in the part 12 of the frame. It is pivoted to the frame by means of a pivot pin 32, as clearly shown in Figure 4. A third arm 33 of the compound lever is connected to one end of a retractile coil spring 34, the other end of which is connected to a portion of an angular extension 35 of the frame 10. The retractile coil spring 34 is tensioned to throw the hammer into firing action as will be herein-after more fully described. 85

Trip or trigger mechanism is provided and includes coacting trip levers 36 and 37. The trip lever 36 has one end pivoted, as at 38, to the extension 35 and the trip lever 37 is pivoted intermediate its ends to the part 11 of the frame, as at 39 (see Figure 2). The adjacent ends of the trip levers are provided with coacting shoulders 40 and 41, respectively, adapted to interlock to releasably secure the trip levers in set or locked position. A detent or sear 42 is carried by the trip lever 36 adjacent its pivot 38 and is adapted to engage and coact with an inclined shoulder 43 provided on the hammer. A trip rod 44 is slidably mounted in the bearing provided therefor in a lateral arm 45 carried by the part 11 of the frame and 100 105

has its inner end offset and received in an eye 46 formed at one end of the trip lever 37. The outer end of the trip rod that is the end remote from the trip lever 37, is pointed or otherwise adapted to receive a corn cob or the like, as shown in Figure 3.

Safety mechanism is provided and includes a pivoted latch 48 mounted upon a lug 49 carried by the angular extension 35 and having a hooked end 50 adapted to engage a curved lug 51 integral with the hammer 27.

In practice, the gun is loaded by removing the barrel from the breech, inserting the shell and replacing the barrel with the shell in place, as shown in Figure 2. The device is then placed near the burrow or hole of the animal and the front leg 14 is driven firmly into the ground to anchor the device and to incline it. The device is so positioned with respect to the burrow or hole that the muzzle of the barrel enters or is immediate to the entrance to the burrow. The finger piece 27^a is then grasped and the hammer 25 is drawn back against the tension of the spring 34 and is then engaged by the latch 48 of the safety mechanism. The trip lever 36 is moved to engage the detent or sear 42 with the inclined shoulder of the hammer 30 and the trip lever 37 is moved to engage the interlocking or coacting shoulders of the trip levers. The trip rod 44, having previously had the corn cob or the like placed on its outer end, is associated with the trip lever 37 and the corn cob on the other end of the trip rod enters the burrow or hole of the gopher or other animal. The safety mechanism is released by swinging the latch 48 upwardly so that its hooked end no longer engages the curved lug 51 of the hammer. The device is then ready for operation.

When the animal contacts with the corn cob or moves the trip rod 44 which is freely slideable in its bearing in the arm 45, this movement of the trip rod swings the trip lever 37 about its pivot and away from the trip lever 36 so that the shoulders 40 and 41 of these levers are disengaged. When the shoulders are disengaged the retractile coiled spring 34 is effective to forcibly throw the hammer against the firing pin. The impact surface of the firing pin and hammer being thus forcibly engaged the striker of the firing pin is projected against the cap of the shell to explode the same. It is obvious that this entire action is practically instantaneous with the movement of the trip rod 44 so that while the gopher contacts with the corn cob which is in the direct line of fire of the gun, the gun is fired and the destruction of the animal is assured.

I claim:

1. In a device of the character described, 65 a two-part frame, fastening means for se-

curing the parts of said frame together, a pair of diverging legs carried by the rear part of said frame, a single leg carried by the forward part of said frame and adapted to be firmly anchored in the ground to incline the frame, a breech carried by the rear part having a cavity therein threaded at its forward end and a bore communicating with the rear of said cavity, a barrel having external threads engaged with the threads of said breech, a firing pin slidably mounted in the firing line of said breech, a hammer for coacting with said firing pin, a compound lever carried by said hammer and having an arm pivoted to said frame, an arm integral with the hammer and a third arm angularly arranged with respect to said other arms, a frame extension rigid with the frame, retractile coil spring connected at one end to the frame extension, and at the other to the third arm of said compound lever and tensioned to throw said hammer into engagement with said firing pin, and trip mechanism including coacting trip levers, a trip rod cooperating with one of said levers and adapted to be actuated by the animal, and a detent carried by the other of said levers and engageable with the hammer.

2. In a device of the character described, 95 a two-part frame, fastening means for securing the parts of the frame together, a pair of diverging legs carried by the rear part of said frame, a single leg carried by the forward part of said frame and adapted to be firmly anchored in the ground to incline the frame, a breech carried by the rear part, a barrel associated with the breech, firing mechanism and trip mechanism controlling said firing mechanism.

3. In a device of the character described, 110 a two-part frame, fastening means for securing the parts of said frame together, a pair of diverging legs carried by the rear part of said frame, a single leg carried by the forward part of said frame and adapted to be firmly anchored in the ground to incline the frame, a breech carried by the rear part of the frame, a barrel associated with the breech, a firing pin slidably mounted in the firing line of said breech, a hammer for coacting with said firing pin, a compound lever carried by said hammer and having an arm pivoted to said frame, an arm integral with the hammer and a third arm angularly arranged with respect to said other arms, a frame extension rigid with the frame, a retractile coil spring connected at one end to the frame extension, and at the other to the third arm of said compound 120 lever and tensioned to throw said hammer into engagement with said firing pin, and trip mechanism including coacting trip levers, a trip rod cooperating with one of said levers and adapted to be actuated by 125 said levers and adapted to be actuated by 130

the animal, and a detent carried by the other of said levers and engageable with the hammer.

4. In a device of the character described, a frame, a breech mounted thereon, a barrel associated with the breech, firing mechanism including a hammer, trip mechanism controlling said firing mechanism and adapted to be released by the animal, a frame extension rigid with the frame and safety mechanism including a latch pivoted to the frame extension and having a hooked

end, the hammer having a curved lug engageable with the hooked end of the latch.

5. In a gun of the kind described, a frame comprising a pair of laterally and downwardly diverging legs intermediate its length and a single shorter leg extending downwardly from its front end, and a barrel mounted on the frame over the front leg and over and between the legs intermediate the length of the frame.

ROBERT FRANCIS ARMSTRONG.
